UNITED STATES PATENT OFFICE.

ALBERT CLEMENS, OF LOUISVILLE, KENTUCKY.

DEVICE FOR DELIVERING MATERIAL FROM A CONTAINER.

1,131,117.

Specification of Letters Patent.

Patented Mar. 9, 1915.

Application filed May 25, 1914. Serial No. 840,963.

To all whom it may concern:

Be it known that I, ALBERT CLEMENS, a citizen of the United States, resident in Louisville, county of Jefferson, State of Kentucky, have invented a new and useful Device for Delivering Material from a Container, of which the following is a specification.

My invention relates to improvements in devices for distributing and delivering material from a container, in which the material is confined in a reservoir and from there is spread in small quantity over a surface adapted to receive it, to be applied from this

surface in the way desired.

The object of my improvement is to provide an easily portable device so constructed that it is easily handled and may if desired be applied as an article of jewelry for the application of cosmetics; that there is no danger of spilling the supply of material, that the amount applied to the distributing surface will be even and not excessive, and at the same time to effect the introduction of the carrying surface into the container and its withdrawal therefrom, by a simple and effective means and to provide a device in which there is at all times some part of the carrying surface exposed to impregnation by the contents of the reservoir.

My invention is shown by the accompanying drawings, in which—

Figure 1 is an end view, Fig. 2 a side view and Fig. 3 a horizontal section through the line X X, omitting the cover.

Similar letters refer to similar parts throughout all of said views.

In the form shown, A is a box which forms a reservoir for the material which is to be delivered. The two sides of the box are segments of a circle, being a little more than a semi-circle. A hinged portion A¹ of a cylindrical part connecting the two sides of the box affords a means of introducing material into the box or reservoir. A block or plate A³ at the top of the box, which block closes the box and forms a part of its walls, is provided with a slit through which the disk shaped flat carrier B slides and has access to the interior of the box A. The dimensions of the slit are such as to allow the passage of the carrier without material leakage of contents.

The carrier B is made of a flexible material suited to the character of material to be delivered and applied, its flat sides being

adapted to pick up and carry material which is in such form that it would tend to adhere. The carrier B is flat and circular and is pivoted at C in such manner that some part of it is always inside the box A and the rest outside, and as it revolves one portion is always entering the box A through the slit and another portion is always emerging from the box A. Two plates B¹ and B², of a thin hard material, are placed adjacent to the center of the carrier B, one on each side of it, to furnish a bearing for the pivot C, which passes through the carrier B and the plates B¹ and B².

A cover D is provided, having in the form shown segmental sides and a cylindrical surface connecting the same, all of such dimensions that, the cover being pivoted concentrically with the box and carrier, it is possible to slide the cover back over the box A, thus exposing the carrier for use and so it can be moved around to such position as to protect the carrier when it is not in use. In the drawing this cover is shown in an intermediate position so that a part of it covers the exposed portion of the carrier and a part of it covers a portion of the box A.

It will be seen that when material is placed inside the box A in proper form, it will come in contact with the carrier B and impregnate the carrier. The carrier B may be grasped with the fingers and turned about the axis C, and when this is done a portion of the carrier will be exposed which has been impregnated with the material, and can be applied wherever the material is to be used. While it is being used for this purpose a new portion of the carrier is within the reservoir, where it is exposed to the contents of the reservoir for impregnation.

It will be seen that the present device has the advantage of flat construction and compactness and that it also furnishes a simple means for returning that portion of the carrier which has been used, and from which the material has been removed by use, back into the container, and that such portion of the carrier is by this device returned into the container without the use of any strings or rods or outside means.

The box can be inverted or shaken without material leakage and its flat construction makes it useful for carrying about in the pocket of the purse. The thin flexible carrier, the flat sides of which are adapted to promote the adherence of the material,

and to facilitate its easy application, render it convenient for the application of material in powdered form, such as a cosmetic powder. The device is so constructed that it may be shaken without material leakage, thus impregnating the entire flat surface of the carrier. My invention also has the advantage that while one portion of the carrier is being used the other portion is in contact 10 with the contents of the box or reservoir A, in preparation for use.

D¹ shows a ring by means of which the device may be attached to a chain or other support. A¹ and A², and D¹ and D² are 15 snaps by which the cover D is caused to remain in place after it has been turned around to a position such that it completely covers the exposed portion of the carrier, and the snaps also serve the purpose of holding 20 the cover in place when folded back over the box.

I claim as new and desire to protect by Letters Patent the following:

1. In a device for distributing and applying material from a container, a flexible circular revoluble carrier, whose flat surface is adapted to be impregnated with material, and a box forming a reservoir and provided

with a slit, said carrier being so placed in relation to the reservoir that as the carrier 30 revolves, portions of the carrier pass through the slit, into the interior of the reservoir and out again through the slit.

2. In a device for distributing and applying material from a container, a flexible 35 circular carrier whose flat surface is adapted to be impregnated by a material in powdered form, plates attached thereto on either side adjacent to the center, a pivot on which said carrier with plates attached is adapted to revolve, and means for impregnating said carrier with material from the reservoir. 40

3. In a device for distributing and applying material from a container, a flexible 45 revoluble carrier to the flat side of which material tends to adhere, and a reservoir fixed adjacent thereto and having a slit through which portions of the carrier move as it revolves, the said slit being of such dimensions that no serious leakage takes place 50 between its sides and the carrier.

ALBERT CLEMENS.
